(57) **CLAIM**

The ornamental design for an automobile front grille, as shown and described.

DESCRIPTION

FIG. 1 is a perspective view of an automotive front grille showing my new design;

FIG. 2 is a front elevational view thereof;

FIG. 3 is a top plan view thereof;

FIG. 4 is a bottom plan view thereof; and,

FIG. 5 is a right-side elevation view thereof, of which the left-side elevation view is a mirror image.

The broken line in the drawings illustrate portions of the automobile front grille that form no part of the claimed design.
